UNITED STATES PATENT OFFICE.

CARL F. SCHEFFER AND JOSEPH ZIMMERMAN, OF DAYTON, OHIO.

BUTTON-PROTECTOR.

1,216,735.

Specification of Letters Patent.

Patented Feb. 20, 1917.

Application filed May 15, 1916. Serial No. 97,754.

To all whom it may concern:

Be it known that we, CARL F. SCHEFFER, a citizen of the United States, and JOSEPH ZIMMERMAN, a subject of the Emperor of Germany, residing at Dayton, in the county of Montgomery and State of Ohio, have invented a new and useful Improvement in Button-Protectors, of which the following is a specification.

10 This invention relates to a new and useful improvement in button protectors.

In cleaning establishments, buttons which are not removed from the garments are frequently broken through forceful contact 15 with the stationary and moving elements of the apparatus and machines which receive them in the process of cleaning and renovating. So great has been the injury to all kinds of buttons from the above cause, that 20 many dry cleaners and laundries employ girls whose sole duty it is to remove the buttons from the garments before the cleaning and renovating operations are started. When this is done, great care must be taken 25 to see that the buttons are not lost or broken after removal, since buttons of special design and rare material are difficult to replace.

It is therefore the principal object of our 30 invention to overcome the above difficulties, at far less expense, by providing a soft and pliable protector for the button to save it from injury while the garment to which it is secured, is in the possession of the cleaner. This protector may be readily applied to, 35 and removed from any sized button, thus making it unnecessary to remove the latter from the garment while it is being cleaned or renovated.

The preferred form of embodiment of 40 our invention is illustrated in the accompanying drawings, of which Figure 1 is a bottom plan view, partly in section, of our button protector. Fig. 2 is a plan view of a garment to one button of which our protector 45 has been applied. Fig. 3 is a side view of the protector. Fig. 4 is a side view of the button hood before the coil spring has been secured thereto. And Fig. 5 is a sectional view taken on the line $a-a$ of Fig. 2, showing 50 the position of the protector on a button.

Throughout the specification and drawings, like reference characters refer to corresponding parts.

In the embodiment of our invention 55 shown in the drawings, the numeral 1 designates a hood or cap constructed of fabric

or other flexible material. This hood is formed substantially as shown in Figs. 2 and 5, having a body portion which completely surrounds the head of the button after its edge portion, which is extensible, has been slipped over the button head and then contracted around the button shank or thread which secures the button to the garment.

To impart rigidity as well as flexibility 65 to the edge portion of the hood 1, there is secured thereto, preferably by means of beads 2, a circumferential coil spring 3. These beads are preferably threaded to the outer edge of the hood so that they may enter between the coils of the springs 3 when the latter are drawn apart. The coils thereof then contract around the threads which hold the beads to the hood 1, and thereby firmly secure the spring 3 to the latter. It 70 is to be understood, however, that we are not confined to this method of securing the spring to the hood 1, as any other suitable means for so doing is within the spirit of our invention.

The hood 1 is now ready to be applied to a button to protect the latter from injury as it accompanies the garment through the cleaning or renovating operations. Figs. 2 and 5 of the drawings show a garment 4 with one of its buttons 5 covered by our protector. It will be observed that the coil spring 3 is contracted around the shank of the button to a diameter of less length than that of its head, while the hood 1 is large 85 and loose above it. The hood therefore forms for the button, a cushion to break the force of its contact with other buttons and parts of the cleaning apparatus, as well as a shield to prevent buttons with jagged 90 points and edges from tearing lace and other flimsy garments during the cleaning or renovating process. It may likewise be applied to weights which, during the cleaning operation, will often wear through the jacket or 100 other garment containing them. It is almost impossible to remove these weights before the cleaning process is started, and when one wears through, the garment which contained it is likely to hang lopsided to the 105 annoyance of the wearer.

Our protector may be made to fit any sized buttons, so that none need be removed before the garments to which they are secured, start through the cleaning or renovating processes.

We do not wish to be limited to the details

of construction and arrangement herein shown and described, and any changes or modifications may be made therein within the scope of the subjoined claims.

5 Having described our invention, we claim:

1. A protector for the buttons of garments while the latter are being cleaned or renovated, comprising a flexible hood for the button, an extensible edge portion on said hood adapted to be readily slipped over the button head and contracted beneath it, and resilient means secured to said edge portion to give rigidity thereto.

2. A protector for the buttons of garments while the latter are being cleaned or renovated, comprising a flexible hood for the button, large and loose above the head of the latter, an extensible edge portion on said hood adapted to be readily slipped over the button head and contracted beneath it, and a resilient element united to said edge portion to give rigidity thereto.

3. A protector for the buttons of garments while the latter are being cleaned or renovated, comprising a flexible hood for the

button, large and loose above the head of the latter, an extensible edge portion on said hood adapted to be readily slipped over the button head and contracted beneath it, and a circumferential coil spring united to said 30 edge portion to give rigidity thereto.

4. A protector for the buttons of garments while the latter are being cleaned or renovated, comprising a flexible hood for the button, an extensible edge portion on 35 said hood adapted to be readily slipped over the button head and contracted beneath it, a coil spring adapted to fit said edge portion in its contracted position, and beads secured to said edge portion for insertion 40 between the coils of said spring to firmly unite the latter to the hood.

In testimony whereof we have hereunto set our hands this 12th day of May, A. D. 1916.

CARL F. SCHEFFER.
JOSEPH ZIMMERMAN.
